(57) **CLAIM**

The ornamental design for a telescopic pool pole, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a telescopic pool pole, showing my new design;

FIG. 2 is front elevation view thereof;

FIG. 3 is a rear view thereof;

FIG. 4 is a right side elevation view thereof;

FIG. 5 is a left side elevation view thereof;

FIG. 6 is an enlarged top plan view thereof;

FIG. 7 is an enlarged bottom plan view thereof;

FIG. 8 is a perspective view thereof, showing the telescopic pool pole in a partially retracted state;

FIG. 9 is an enlarged fragment of the portion of the telescopic pool pole shown in FIG. 8 and labeled 9;

FIG. 10 is a partial perspective view thereof, showing the telescopic pool in a fully retracted state; and,

FIG. 11 is a partial perspective view thereof, showing the telescopic pool in a partially retracted state.

Color forms part of the claimed design.
